UNITED STATES PATENT OFFICE.

ERNEST F. WIEDERHOLDT, OF ST. LOUIS, MISSOURI.

INSULATED SPARK-PLUG CONNECTER.

Application filed December 5, 1921. Serial No. 519,980.

To all whom it may concern:

Be it known that I, ERNEST F. WIEDERHOLDT, a citizen of the United States, residing at St. Louis, Missouri, have invented 5 a certain new and useful Improvement in Insulated Spark-Plug Connecters, of which the following is a full, clear, and exact description, such as will enable others skilled in the art to which it appertains to make 10 and use the same.

This invention relates to spark plug connectors, and has for one of its objects to provide an inexpensive spark plug connector that can be used with various kinds of spark 15 plugs now in commercial use, and which is compact and of such construction that the metallic parts of the connector and the portion of the electrode of the plug with which the connector co-operates are completely protected by insulating material.

Another object is to provide a spark intensifier of novel design, which is constructed in such a manner that there is no liability of the length of the spark gap being increased, due to burning of one or the other 25 of the electrodes arranged at opposite sides of the spark gap. Other objects and desirable features of my invention will be herein-after pointed out.

30 Figure 1 of the drawings is a side elevational view, illustrating my improved connector applied to a conventional spark plug.

Figure 2 is a longitudinal sectional view of said connector.

35 Figure 3 is a transverse sectional view of said connector, taken on the line 3—3 of Figure 2; and

40 Figure 4 is a vertical longitudinal sectional view of a combined insulated spark plug connector and spark intensifier constructed in accordance with my invention.

Referring to Figures 1, 2 and 3 of the drawings, which illustrate one form of my invention, A designates a conventional 45 spark plug provided with an externally screw-threaded electrode 1 that projects upwardly above the upper end of the insulator 2 of the spark plug. The supply wire B through which the electric current is conducted to the spark plug A is detachably connected to the electrode 1 of the plug by my improved connector which is composed of a member C of insulating material, a metal part 3 inside of the insulator C to

which the supply wire is connected and a 55 separate metal part 4 inside of the insulator connected to the metal part 3 and provided with a bore 5 for receiving the electrode 1 of the spark plug. The insulator C may be of any preferred shape, but it is preferably 60 of substantially spherical form and is provided with two right-angularly-disposed bores in which the metal parts 3 and 4 are loosely mounted, thereby enabling the connector to be manufactured at a low cost, due 65 to the fact that it is not necessary to mold the insulator of the connector around the metallic parts of the connector or permanently secure said metallic parts and insulator together. In the form of my invention 70 shown in Figures 1, 2 and 3 the metallic part 3 consists preferably of a tubular member horizontally arranged in the insulator C and provided on its underside with an internally screw-threaded hole 6, the conducting portion α of the supply wire B projecting into said member 3, as shown in Figures 2 and 3. The metallic part 4 of the connector is arranged in the bore or opening on the underside of the insulator C and is 80 provided with an externally-screw-threaded portion 7 that projects upwardly into the internally-screw-threaded hole 6 in the metallic part 3 of the connector, said portion 7 being long enough so that it will engage and securely clamp the conducting portion α of the supply wire to the metallic part 3 of the connector. Accordingly, the portion 7 of the metallic part 4 performs the 85 dual function of retaining the two metallic parts 3 and 4 in the insulator C and securely connecting the supply wire to said metallic part 3.

The means that I prefer to use for holding the connector as an entirety in operative 90 position on the spark plug A consists of two metal balls 8 mounted in the metallic part 4 in such a manner that they will project into the bore 5 of the metallic part 4, and thus engage the electrode 1 of the spark plug, 100 and coiled expansion springs 9, shown in Figure 2, that back up the balls 8, and cause same to frictionally engage the electrode 1 of the spark plug in such a way as to eliminate the possibility of the connector becoming accidentally detached from the spark plug. It is not absolutely essential that the connector be equipped with two balls 8, but

I prefer to construct the connector in this manner so as to enable it to be used with a spark plug provided with an electrode of small cross-sectional diameter, or with a 5 spark plug provided with an electrode of large cross-sectional diameter. In other words, when the metallic part 4 of the connector is provided with two oppositely-disposed balls 8 that project into the bore 5 of 10 said metallic part that receives the electrode of the plug, as herein shown, the connector will be held securely in operative position on the spark plug, irrespective of whether the spark plug is provided with a small electrode 15 or a large electrode. The springs 9 that back up the balls 8 are retained in operative position in the metallic part 4 by a split ring compression spring 10 that surrounds the metallic part 4 and which is seated 20 in an annular groove in said metallic part. The metallic part 4 is preferably provided on its underside with a transversely-disposed groove or slot 11 in which a screw-driver can be inserted during the operation 25 of screwing the externally-screw-threaded portion 7 of the metallic part 4 into the internally-screw-threaded hole 6 in the metallic part 3 of the connector.

A spark plug connector of the construction 30 above described can be manufactured and sold at a low cost; it can be easily applied to or removed from a spark plug without liability of subjecting the user to an electric shock, due to the fact that the metallic parts of the connector through which the 35 electric current passes are completely protected by insulating material; it can be used with practically any make of spark plug provided with an electrode that projects upwardly above the insulator of the plug, and it is so constructed that there is little liability of its becoming accidentally detached from the spark plug, due, of course, to the fact that it comprises a plurality of spring- 40 pressed elements that are held pressed tightly against the electrode of the spark plug.

As previously stated, one object of my invention is to provide a spark intensifier in which the electrodes are of such construction and arrangement that they will not be burned by the intense spark created at the 45 gap, and thus cause the length of the spark gap to be increased, as so often occurs with the spark intensifiers now in use. To this end I have devised a spark intensifier which may be described briefly as consisting of two electrodes having relatively large areas arranged in an electric circuit in spaced relation and in parallel planes, so as to form a gap across which the electric current flowing through said circuit jumps. The form and size of said electrodes is immaterial, so long as said electrodes have sufficient area to prevent them from being burned away by the 50 intense sparks that jump across the gap be-

tween said electrodes, and it is also immaterial what means is used for holding said electrodes in spaced relation, so as to produce a spark gap between them. I prefer, however, to make said electrodes of annular form 55 and arrange them in parallel planes with a gap or space between the adjacent faces or inner sides of said electrodes. In Figure 4 of the accompanying drawings I have illustrated a spark intensifier of the character 60 above referred to combined with a spark plug connector of the kind previously described, said connector being of similar construction to the one shown in Figures 1, 2 and 3, except that the metallic part to which the supply wire B' is connected is provided with a gap 12 across which the electric current jumps before reaching the metallic part 65 that receives the electrode 1 of the spark plug. It is immaterial how the gap 12 is formed, but I prefer to use a metallic part or electrode 3^b to which the conducting portion α of the supply wire is connected by a set screw or other device 13 and hold said electrode 3^b in spaced relation with the outer end of a metallic part or electrode 3^a by means of a piece of insulating material 14 that is secured to the metallic part 3^a and the part 3^b by means of rivets 15, or the like, 70 the space between the outer end of the electrode 3^a and the inner end of the electrode 3^b constituting the gap of the intensifier. Preferably, the spaced end portions of the electrodes 3^a and 3^b across which the spark jumps, are of annular form, as I have found 75 that a spark gap formed by two spaced annular rings or portions is superior to a spark gap formed by two points, prongs or similar devices spaced away from each other in that they will not burn away, and thus increase 80 the length of the spark gap. The part 3^b projects laterally from one side of the insulator C and is surrounded by a sleeve of insulating material 16 provided with an inwardly-projecting flange 16^a that is overlapped by a head or enlarged portion on the part 3^b, as shown in Figure 4, thus causing 85 the insulating sleeve to be retained in position by the part of the connector to which the supply wire is fastened. A connector 90 of the construction shown in Figure 4 has all of the desirable characteristics of the connector shown in Figures 1, 2 and 3, and it has the added advantage of being constructed in such a way that it will intensify the 95 spark which the spark plug produces when in service. To convert the connector shown in Figure 2 into a combined spark plug connector and spark intensifier, all that is necessary is to substitute for the metallic part 3 the two-piece member composed of the parts 3^a and 3^b, as shown in Figure 4, the metallic part 4^a of the connector which receives the electrode of the spark plug performing the same function in the combined 100

connecter and spark intensifier that it performed in the insulated spark plug connecter shown in Figure 2.

Having thus described my invention, what I claim as new and desire to secure by Letters Patent of the United States is:

1. A spark plug connecter consisting of an insulator, a metallic means in said insulator provided with a spark gap and adapted to have a supply wire connected to same, and a metallic member in said insulator connected to said means and provided with a spring-pressed element for frictionally connecting said member to the electrode of a spark plug.

2. A spark plug connecter, comprising a metallic part provided with a bore for receiving the electrode of a spark plug and equipped with a spring-pressed element for frictionally engaging said electrode, an independent metallic means connected to the metallic part first referred to and adapted to have a supply wire secured to same, said metallic means being provided with a spark gap, and insulating material that completely protects said metallic part and said metallic means.

3. A spark plug connecter consisting of an insulator provided with two bores arranged at an angle to each other, a spark gap device in one of said bores composed of two metal parts spaced away from each other and connected together by insulating material, one of said parts being provided with means for enabling a supply wire to be connected to same, and a metallic member in the other bore of said insulator equipped with a spring-pressed element for frictionally connecting same to a spark plug electrode and

provided with a screw-threaded portion that is screwed into an opening in one part of said spark gap device.

4. A spark plug connecter consisting of a spherical-shaped insulator provided with two bores arranged at substantially right angles to each other, a metallic member in the horizontal bore of said insulator provided at its outer end with a piece of insulating material, a metallic device connected to said piece of insulating material and provided with a head portion to which a supply wire is adapted to be connected, an insulating sleeve surrounding said head portion and provided with a flange that is positioned between said head portion and the insulator of the connecter, and a second metallic member in the vertical bore of the insulator detachably connected to the metallic member in said horizontal bore and provided with a plurality of spring-pressed balls that are adapted to frictionally engage the electrode of the spark plug with which the connecter is used.

5. A spark plug connecter, consisting of an insulator, two electrodes carried by said insulator and arranged in longitudinal alignment with each other and with annular portions on the inner ends of said electrodes spaced apart so as to form a spark gap, means for maintaining the annular portions of said electrodes in fixed relation, means for enabling a supply wire to be connected to one of said electrodes, and a metallic member in said insulator connected to the other electrode for securing the insulator to the electrode of a spark plug.

ERNEST F. WIEDERHOLDT.
